COSMETIC CONTAINING CASE

René Mortier, Paris, France, assignor to Société à Responsabilité Limitée G. Rolot & H. Lemasson, of Route de Dijon et Beaune, Côte d'Or, France

Application December 31, 1931, Serial No. 584,248
In France February 3, 1931

2 Claims. (Cl. 206—56)

The present invention relates to a case which is provided with a ring, a capsula or any other element sliding within the case, acted upon by a pusher at the outer surface of the apparatus, 5 and supporting the product to be presented.

The pusher cooperates with a link serving for opening and closing the cover of the case, with aid of a pivot or any other part integral with the said ring, capsula or the like, in such manner that the first part of the pusher stroke causes the opening of the cover whereas the following part of the pusher stroke brings forward the product or object contained in the case, in any desired length.

On acting in the inverse manner, first the product or object is entered into the case and then the cover gets closed.

The invention will be better understood in the course of the following description relating to the drawing appended.

In the drawing represents:

Fig. 1 an outer view of a case according to the invention, and containing a paint stick;

Fig. 2 a section according to the lines 2—2 of Fig. 4, the cover being in the closed position;

Fig. 3 a similar view, the cover being in the opened position, and

Fig. 4 a section according to the lines 4—4 of Fig. 2.

The case according to the invention and shown merely in the way of example, is one for paint, the paint stick 1 being inserted with one of its extremities into a capsule 2. This capsule slides in the interior of the case 3 and is controlled from the exterior by a pusher or button 4 integral with or connected to the capsule and sliding in a slot 5 provided in the case and of suitable length.

The cover 6 oscillates around small pivots 7 and is connected to a link 8 by a pivot 9 traversing the case and sliding in a slot 10 forming one fourth of a circle with the axis of the pivot 7 as its center.

In the closed position of the cover the rod 4a of the pusher is in the lower part of the slot 5.

On pushing the pusher upwardly, the rod 4a tends to remove the link 8 laterally from the left to the right; but, since the lateral displacement depending on the inner width of the case and 50 the corresponding width of the link is less than the length of the notch, 11, provided in the link, the tail 12 of the link will abut against the inner wall of the case.

Hence it follows that the link is prevented 55 from lateral deviation and that it is obliged to

follow the upward movement of the pusher 4, and to open the cover pivoting around its pivots 7.

On opening the cover the link is, owing to the movement of the pin 9 in the slot 10, moved laterally, so that the pin 4a of the pusher 4 becomes disengaged from the slot 11, and the pusher is permitted to move up to the upper part of the case.

An important particularity of the case consists in that it is prevented from opening prematurely. This result is obtained in the following way:

The lower part of the slit 5 is widened to a recess 14 to which corresponds a tooth 15 provided on the link 8. In the closed position, the tooth 15 engages the recess 14 of the slit 5. It is obvious that in this position the link is prevented from moving laterally because the pusher 4 immobilizes the link in this direction. Hence the cover cannot be opened by exerting a pull upon the same; consequently the case cannot casually open in a reticule. In order to permit the opening, it is necessary to push the pusher 4 upwardly, the pusher rod 4a acting upon the inclined wall of the notch 11 of the link so that the latter moves slightly from the left to the right without causing abutment of the tail 12 against the inner wall 3a of the case. This slight displacement suffices to free the tooth 15 and permits the ascension of the link and hence the opening of the cover.

The plate forming the link 8 is arranged in such manner that it covers the slot provided for the passage of the rod 4a of the button 4. It follows that the product contained in the case, which in the example shown is a paint stick, cannot dry and is protected against dust.

It goes without saying that the invention is not limited to the example described and that it permits of manifold modifications both with regard to the general shape and to the details without departing from the scope of the present invention.

The case could be, for example of square, rectangular, elliptic, polygonal or any other section, the cover can oscillate rearwardly or laterally, and so on.

The product contained in the tube can be of any kind, for example lead, india rubber, any pharmaceutical stick, such as salt, a stick of argentum nitricum, or a perfume bottle, a bottle containing another liquid, a lighter, a spark controller, and so on, an electric lamp, and so on.

What I claim is:

1. A case, a cover for the case pivotally con-

nected thereto, said case having a curved slot concentric with the pivot of the cover and also having a longitudinal slot, a product holder in the case, a pusher for actuating said holder and 5 having a pin movable in said longitudinal slot, a link pivotally connected to the cover, the pivot of said link being movable in said curved concentric slot and said link having an inclined open slot near its free end for engagement by 10 the pin of the pusher and also having a tooth, the said longitudinal slot of the case having a recess in its lower end for engagement by said tooth.

2. A casing, a cover pivotally connected thereto, said casing having a longitudinal slot, a product carrier sliding in the said casing, means connecting the product carrier to the cover and consisting of a band or strap fastened in such a way as to pivot on the cover, the pivot of the

said strap being movable in a slot in the casing and concentric to the said pivot, and the said strap having an open inclined slot near its free end for engagement of the sliding finger of the pusher which pushes back the said strap upon the beginning of the stroke of the pusher and causes pivoting of the cover, the said finger re-entering the said inclined slot at the end of the course of the pusher in order to act on the strap and close the cover, means for maintaining the strap in a closure position of the cover constituted by a tooth fixed to the base of the strap, a shoulder being made in the longitudinal slot of the casing at the lower part of the latter for engagement of the above mentioned tooth in the shoulder at the end of the descent of the pusher and the product carrier. 5 10 15
